UNITED STATES PATENT OFFICE.

JOSEPH W. McGALLIARD, OF LOS ANGELES, CALIFORNIA, ASSIGNOR OF ONE-HALF TO
NICHOLAS A. D'ARCY, OF LOS ANGELES, CALIFORNIA.

SPRING ADJUSTMENT FOR CONCENTRATORS.

1,369,898.

Specification of Letters Patent. Patented Mar. 1, 1921.

Application filed October 5, 1918. Serial No. 257,810.

To all whom it may concern:

Be it known that I, JOSEPH W. McGALLIARD, a citizen of the United States, residing at 7619 Whitsett avenue, in the city of 5 Los Angeles, county of Los Angeles, and State of California, have invented a new and useful Spring Adjustment for Concentrators, of which the following is a specification.

10 This invention relates to concentrators comprising a reciprocating table provided with ore separating means on its surface.

It is customary with tables of this character that the same shall be supported on 15 springs that are arranged to yield in the direction of the reciprocation or oscillations of the table.

An object of this invention is to provide 20 an improved resilient support for the table whereby the table may be accurately adjusted to any desired level for the purpose of regulating the concentrating action of the table as it is reciprocated.

Another object is to make provision 25 whereby crystallization of the springs is minimized.

Simplicity, strength and low cost are other objects in view.

Apparatus of the kind to which this invention relates requires very delicate adjustment in order to obtain the desired separation and such adjustment is likely to be required at every change in the character 30 of the ore which is to be separated by the table and it is important that when said adjustment is made that it will remain as established without any danger of disarrangement. Otherwise great losses of value 35 might occur through inattention or overconfidence of the attendant; and an object of my invention is to provide more simple inexpensive and also more effective means for securing and maintaining the adjustment than has heretofore been known; thus 40 to greatly improve the operation of concentrators.

Further objects and advantages may appear from the accompanying drawing, the subjoined detail description and the appended claims.

The accompanying drawing illustrates the invention.

Figure 1 is a side elevation of a concentrator table having adjustable means constructed in accordance with this invention.

Fig. 2 is an end elevation of the table and its supports.

Fig. 3 is an enlarged fragmental transverse elevation of one of the adjustments with portions of the table and base in section on line x^3 , Fig. 1.

Fig. 4 is a fragmental side elevation of one of the adjustments with fragments of the table in place.

Fig. 5 is a plan section on line x^5 , Fig. 4. 65

Fig. 6 is a plan section on line x^6 , Fig. 4.

Fig. 7 is an enlarged section on irregular line x^7 — x^7 , Fig. 3.

Fig. 8 is an enlarged inverted plan section on line x^8 , Fig. 7. 70

1 indicates concentrator table reciprocating mechanism of a common type connected as indicated at 2 to reciprocate the table 3 which is represented as being of the type illustrated in my co-pending application 75 for patent on ore concentrator, Serial No. 257,811, filed contemporaneously herewith.

The supporting springs 5 are arranged in pairs at several transverse vertical planes of the table, in the usual manner; one member 80 of each pair being shown in Fig. 1 and one pair being shown in Fig. 2.

5 indicates the bed which supports the entire structure and the same may be made of wooden or other sills or may be a concrete 85 foundation or any other firm solid construction adapted to sustain the table and its operating mechanism. Any desired form of construction may be employed for the bed 5.

Upon said bed are mounted pedestals each 90 formed of a base plate 6 having holes 7 therethrough to receive fastening devices 8. Upon the base plate 6 is mounted an internally threaded seat 9 provided with internal threads 10 to receive an adjustable 95 externally threaded socket 11 having a wrench-receiving head 12 and screwed into the threaded seat 9 and provided with a jam nut screwed onto the threaded socket 13 between the wrench head flange 12 and the 100 seat 9 to jam upon the seat 9 to preserve a desired adjustment.

The bore 14 of the socket piece 11 is adapted to receive the substantially vertical cylindrical stem 15 of the swivel spring support 16 which is provided with two jaws 17, 18, through which the clamp bolt or screw 19 is inserted; the same being free to slip in the jaw 17 and screwed into the jaw 18. The space 20 between said jaws is adapted 110

to receive the lower end of the steel or other spring 4 and also a resilient member or cushion 21, of leather or rubber, arranged so that by tightening the clamp bolt 19 the 5 spring and cushion are tightly gripped together thus affording a firm but yielding tight and noiseless connection which will minimize the likelihood of spring crystallization.

- 10 The bifurcated top fixtures 22 have downwardly extending jaws 23 and 24 between which are secured the upper ends of the springs 4 by clamp bolts or screws 25. The jaws 23, 24, screws 25, and cushion members 15 26 of the top fixtures are similar in construction to corresponding parts of the base supports 16. The upper ends of the fixtures 22 are pivotally secured by bolts 27 to hangers or depending bearings 28 that are 20 integral with the top plates 29 which latter have holes 30 for screws 31 by which they are secured to the table 3.

In practical operation the springs, which may be of any suitable cross-sectional form, 25 acting against the cushions 21, will be relieved of much of the destructive stress and strain that is likely to cause crystallization at either top or bottom connections of the springs. Said springs are shown as being 30 flat as that form is at present deemed most practical and convenient. It is understood, however, that I do not limit the invention to the specific construction shown.

To adjust the table the appropriate lock 35 nuts 13 will be loosened, the threaded sockets 12 will be screwed up or down as may be required to bring the table top to the desired angle or inclination cross-wise and endwise and then the lock nuts 13 will be 40 made tight.

By screwing all the sockets 12 on one side of the table, such side may be raised or lowered accordingly. Lengthwise or endwise slope adjustment may be effected by adjusting such sockets on both sides.

The adjustment of the table may be made to a minute degree.

When the table is finally brought to the required angle, the set nuts 13 will be 50 tightened and the table is ready for use.

It is thus seen that I have provided in combination with a support, comprising the bed 5, and with a concentrator top as shown at 3, and with the springs 4, extending up 55 and down to support the table; adjustable swivel joint connections between the support and the spring ends as at 9, 11, and 16 at one end of the spring, and hinge joint connections as at 22, 27, 28, between the table 60 top and the spring ends at the other end of the springs; and that the lower connections are threaded adjustments whereby the space between the base plate 6, may be adjusted and that such adjustment may then be fixed 65 by setting the jam nut 13 as stated, and

which may be released when it is desired to change the adjustment, so that the operation of adjusting the level or slant of the table to practically a hair's-breadth so as to effect the required separation, is easy.

It is deemed most satisfactory to arrange the springs below the table in accordance with a common practice, but I do not limit the invention to such arrangement. It is also preferable to make the swivel connection at the end attached to the support and the joint connection at the end attached to the table as this arrangement gives a requisite flexibility and is easily adjusted.

The plates 29 are preferably let into gain 32 in the side rails 33 of the table top so as to make the connection between the table top and the hanger 28 firm and rigid. Said hangers are short and rigid knuckles or eyes so that the pins or bolts 27 of the hinge 85 joints will be close to the rails.

The reciprocating mechanism is connected to the table top in the usual way and resiliently holds the same in operating position.

In conclusion, it should be noted that, 90 while the adjustment means positively maintain the concentrator table 3 in adjusted relation to the bed 5, the arrangement of the supporting springs upon substantially vertical axes allows a certain torsional 95 movement of the springs during the operation of the concentrator in order to compensate for any unevenness in the springs tending to produce a torsional movement whereby the durability of the springs may be impaired. By my arrangement, therefore, the deleterious effect of such torsional tendency is counteracted, and the durability and the longevity of the springs is thereby maximized.

I claim,

1. A spring adjustment for concentrators comprising a seat provided with internal threads; an adjustable, externally threaded socket provided with a longitudinal bore 110 and having a wrench-receiving head and screwed into the threaded seat; a spring-carrying support rotatably mounted in said bore and a jam nut screwed onto the threaded socket between the wrench head and the seat 115 to jam upon the seat to preserve a desired adjustment.

2. A spring adjustment for concentrators comprising a seat provided with internal threads; an adjustable, externally threaded socket having a wrench receiving head and screwed into the threaded seat; a jam nut screwed onto the threaded socket between the wrench head and the seat to jam upon the seat to preserve a desired adjustment; 120 a spring support pivoted on a substantially vertical axis in the socket; and means to clamp a spring to said support. 125

3. The combination with a spring, of a swivel spring support which is provided 130

with two jaws and a clamp bolt or socket free to slip in one of the jaws and screwed into the other jaw; a cushion between the jaws; the space between said jaws being adapted to receive the cushion and the lower end of the spring; said cushion being arranged so that by tightening the clamp bolt the spring and cushion are tightly clamped together.

10 4. The combination with a spring of a swivel spring support provided with a substantially vertical, cylindrical stem; a socket for the stem of the swivel spring support; and means to secure one end of the spring 15 in the spring support.

5. The combination with a spring of a swivel spring support provided with a substantially vertical, cylindrical stem; a socket for the swivel stem of the spring support; 20 means to secure one end of the spring in the spring support; a top fixture having downwardly extending jaws; and means to connect the spring to the fixture.

6. The combination with a support, a concentrator top, and springs extending up and down to support the table top; of connections between the support and the springs at one end of the springs; and connections between the table top and the other ends of 30 the springs; the connections at one end of said springs being swivel connections arranged on substantially vertical axis and the connections at the other ends of said springs being hinge connections.

35 7. The combination with a support, a concentrator table top, and springs extending up and down to support the table top; of swivel joint connections arranged on sub-

stantially vertical axes between the support and the spring ends farthest from said table 40 top and hinge joint connections between the table top and the spring ends nearest to said top.

8. The combination with a support, a concentrator table top, and springs extending 45 up and down to support the table top; of swivel joint connections arranged on substantially vertical axes between the support and the lower ends of the springs; and hinge joint connections between the table top and 50 the upper ends of the springs.

9. The combination with a support, a concentrator table top, and springs extending up and down to support the table top; of swivel joint connections arranged on substantially vertical axes between the support and the springs at one end of the springs; 55 hinge joint connections between the table top and the other ends of the springs, said connections comprising cushions; and means 60 whereby the cushions are clamped onto the spring ends.

10. The combination with a concentrator table top and a base, of a spring extending up and down; a hinge connection connecting 65 the upper end of the spring with the table top; and a swivel connection arranged on a substantial vertical axis and comprising a threaded adjustment connecting the spring to the base. 70

In testimony whereof, I have hereunto set my hand at Los Angeles, California, this 25th day of September, 1918.

JOSEPH W. McGALLIARD.
